Attorney, Agent, or Firm—Van Dyke, Gardner, Linn & Burkhardt, LLP

[57] CLAIM

The ornamental design for a rearview mirror assembly, as shown and described.

DESCRIPTION

FIG. 1 is a top, front perspective view of a first embodiment of the rearview mirror assembly showing our new design; FIG. 2 is a bottom, front perspective of FIG. 1; FIG. 3 is a front elevation of FIG. 1; FIG. 4 is a rear elevation of FIG. 1; FIG. 5 is a top plan view of FIG. 1; FIG. 6 is a bottom plan view of FIG. 1; FIG. 7 is a left end elevation of FIG. 1;

FIG. 8 is a right end elevation of FIG. 1;
FIG. 9 is a top, front perspective view of a second embodiment of the rearview mirror assembly showing our new design;
FIG. 10 is a bottom, front perspective of FIG. 9;
FIG. 11 is a front elevation of FIG. 9;
FIG. 12 is a rear elevation of FIG. 9;

FIG. 13 is a top plan view of FIG. 9;
FIG. 14 is a bottom plan view of FIG. 9;
FIG. 15 is a left end elevation of FIG. 9; and,
FIG. 16 is a right end elevation of FIG. 9.
